United States Patent Office

Des. 215,327
Patented Sept. 23, 1969

215,327

POCKET WATCH OR THE LIKE

Mel Appel, Short Hills, N.J., assignor to General Time Corporation, Stamford, Conn., a corporation of Connecticut

Original design application Apr. 14, 1967, Ser. No. 6,706.
Divided and this application Oct. 24, 1967, Ser. No.
9,301

Term of patent 14 years

Int. Cl. D10—02

U.S. Cl. D42—8

FIG. 2

FIG. 1

FIG. 3

FIG. 4

FIG. 6

FIG. 7

FIG. 5

FIG. 1 is an exploded front elevation view of a pocket watch or the like showing my new design in open condition;

FIG. 2 is a top plan view thereof;

FIG. 3 is an edge elevational view thereof in open condition;

FIG. 4 is an exploded rear elevational view thereof in open condition;

FIG. 5 is a bottom plan view thereof;

FIG. 6 is an elevational view thereof in closed condition; and

FIG. 7 is an edge elevational view thereof in closed condition.

The essential features of the design are shown in full lines.

This application is a division of my copending design patent application, Ser. No. 6,706, filed April 14, 1967, and entitled "Pocket Watch or the Like."

I claim:

The ornamental design for a pocket watch or the like, substantially as shown and described.
